UNITED STATES PATENT OFFICE.

CHARLES C. FARDON, OF TULSA, OKLAHOMA, ASSIGNOR OF THREE-FOURTHS TO FLOYD A. SANDERS AND ONE-FOURTH TO DELLA L. SANDERS, BOTH OF TULSA, OKLAHOMA.

STORAGE-TANK.

1,218,600.

Specification of Letters Patent. Patented Mar. 6, 1917.

Application filed June 6, 1916. Serial No. 102,063.

To all whom it may concern:

Be it known that I, CHARLES C. FARDON, a citizen of the United States of America, and resident of Tulsa, in the county of Tulsa 5 and State of Oklahoma, have invented certain new and useful Improvements in Storage-Tanks, of which the following is a specification.

This invention relates to storage tanks 10 and particularly to tanks for storing oil or other volatile commodities, the said invention being directed primarily to the provision of novel means for preventing undue evaporation of the contents of the tank and 15 to obviate the presence of a plurality of leaks where the gas may escape and endanger the tank or its contents as where lightning might ignite the escaping gas and cause fire.

20 A further object of this invention is to provide a tank with a leak-proof joint between the roof and the wall of said tank, it being well known that it is commonly a great loss and annoyance when the joint between 25 the roof and tank is unsealed.

With the foregoing and other objects in view, the invention consists in the details of construction, and in the arrangement and combination of parts to be hereinafter more 30 fully set forth and claimed.

In describing the invention in detail, reference will be had to the accompanying drawings forming part of this specification wherein like characters denote corresponding parts in the several views, and in which—

Figure 1 illustrates a view in elevation of a tank with the vent tubes, the supports for the vent tubes being shown in section; and

40 Fig. 2 illustrates a vertical sectional view of a fragment of the tank showing the roof and the joint between the roof and the tank.

In these drawings 3 denotes a tank, 4 the usual board or plank covering for the tank, 5 the sheathing or metal covering for the wooden portion of the roof, the said sheathing 5 extending beyond the wall of the said tank and embracing the flange 6 of the angle iron 7, the said angle iron having 45 one wing 8 thereof lying parallel with the side of the tank and secured thereto by fastenings 9 which may be in the form of bolts, rivets or the like. It is probably preferable, although not essential in all instances, that a packing 10 be interposed between the an-

gle iron and the wall of the receptacle so as to prevent formation of crevices or pockets in which gas might lodge.

The sheathing 5, as stated, embraces the edge of the flange 6 and the sheathing is 60 secured to the said flange by the fastenings 11 which may comprise bolts, rivets or the like.

The metal covering is then caused to embrace the angle iron and the opposite edge 65 of the metal covering is bent to lie between the angle iron and the tank and it is clamped in place and firmly held by the fastenings which are employed to secure the angle iron to the tank. It is preferable also 70 to utilize a metal covering 13 for embracing the angle iron 7, so as to obviate the formation of pockets for the collection of gas and as a further means for safe-guarding the structure against leaks and the formation of 75 pockets, the space inclosed by the angle iron and the metal covering is supplied with a filler 14 consisting of an asphalt preparation.

From the foregoing, it will be seen that in 80 view of the fact that the usual pocket formed by the angle iron 6, is filled by the material 14, which is held in position by the asbestos 13, any danger of gas which might leak from the tank and collect at this 85 point is obviated, thereby lessening the liability of explosion or fire, due to lightning igniting escaping gas.

I claim

1. A storage tank having a roof including a metal covering therefor, an angle iron secured to the tank near its upper end, the said covering being extended to embrace the edge of a flange of the angle iron, means for securing the covering to the said angle 90 iron, a metal member secured to the roof and embracing the angle iron and having its edge interposed between the said angle iron and the tank, and a filler between the metal member and the angle iron. 95

2. A storage tank having a roof including a metal covering therefor, an angle iron secured to the tank near its upper end, the said covering being extended to embrace the edge of the flange of the angle iron, means for securing the covering to the said angle 100 iron, a metal member secured to the roof and embracing the angle iron and having its edge interposed between the said angle iron and the tank, a filler between the metal 105 and the angle iron. 110

member and the angle iron, and a filler between the angle iron and the tank.

3. A storage tank having a roof including a metal covering therefor, an angle iron secured to the tank near its upper end, the said covering being extended to embrace the edge of the flange of the angle iron, means for securing the covering to the said angle iron, a metal member secured to the roof and embracing the angle iron and having its

edge interposed between the said angle iron and the tank, and suitable insulation and crevice filling material associated with the tank, angle iron and metal member.

In testimony whereof, I hereunto affix my 15
signature in the presence of two witnesses.

CHARLES C. FARDON.
